UNITED STATES PATENT OFFICE.

REINHARD L. HEEREN, OF BROOKLYN, NEW YORK

DETACHABLE REVERSIBLE CUFF.

1,314,326.

Specification of Letters Patent. Patented Aug. 26, 1919.

Application filed May 19, 1919. Serial No. 297,893.

To all whom it may concern:

Be it known that I, REINHARD L. HEEREN, a citizen of the United States, and a resident of the borough of Brooklyn, county of 5 Kings, city and State of New York, have invented certain new and useful Improvements in Detachable Reversible Cuffs, of which the following is a specification.

While applicable to the sleeves of other 10 garments, my improvements are designed more particularly for use in connection with shirts, waists, etc., made of relatively soft, unstarched material, and where one part of each cuff folds back over and outside 15 the part thereof which is attached to the sleeve. The main object of my invention is to afford simple but effective means whereby the cuffs are rendered conveniently detachable, reversible, and interchangeable, 20 while presenting when attached to the sleeves, the appearance of being integral therewith. In other words, I positively conceal the fact, in so far as outward appearance is concerned, that the cuffs are not permanently attached to the sleeves, giving the 25 effect of a unitary structure.

The invention consists in the specific construction and arrangement of parts herein described and claimed, a distinctive feature 30 being the provision of sleeve flaps adapted to conceal the means of attachment between the sleeve wrist bands and the detachable cuffs, all as hereinafter more fully set forth.

In the accompanying drawings,

35 Figure 1, is a view of the exterior of the cuff as attached to the sleeve wrist band, the parts being shown flat for convenience of illustration;

Fig. 2, is a similar view with the cuff 40 unfolded and showing the concealment flap overlapping the cuff attaching means;

Fig. 3, is a view of the sleeve wrist band and concealment flap, the latter being folded back against the sleeve to expose the cuff 45 securing means;

Fig. 4, is a view of either side of the cuff spread out flat, and showing the use of metallic socket button holes for engagement with the stud buttons on the sleeve 50 wrist band;

Fig. 5, is a like view of the cuff showing the use of slit button holes for engagement with the stud buttons on the sleeve wrist band;

55 Fig. 6, is an enlarged sectional detail showing the preferred construction of the

sleeve wrist band and concealment flap out of a single piece of material;

Fig. 7, is a similar enlarged sectional detail illustrating in a general and necessarily exaggerated manner the attachment and correlation of the parts when the cuff is applied to the sleeve wrist band.

As shown in the accompanying drawings, the concealing flap A, and the wrist band B, are formed of a single piece of fabric, although this is not an essential feature of my invention, since said concealing flap A, may consist of a suitable width and length of material independently attached to the sleeve S. The wrist band B, is three ply, consisting of the terminal margin s, of the sleeve S, and of the overlapping and inclosing inner and outer folds b, b', of the band proper B.—b², b², representing the stitching 75 by which the parts are secured together, the line of stitching b², in the present case also passing through the inner edge of the concealing flap A. The width of the said concealing flap A, is greater than that of the 80 sleeve wrist band B, so that when folded over the latter its free edge a, extends beyond the outer edge of said band B, as shown in Figs. 2, 6 and 7. Protruding from the outer 85 face or fold b', of the wrist band B, are a series of stud buttons b^x, b^x, attached to the said band in any suitable manner, as may be found most expedient. These stud buttons b^x, b^x, are of course concealed by the flap A, when the latter is folded over the 90 wrist band B. a', is the line of stitching securing the inturned outer edges of the concealing flap A. The ends a², a², of the latter are sloped obliquely and convergently 95 inward centrally from the base line of attachment to the sleeve S, so as to afford convenient access to the usual cuff link or button holes c, c, in the body of the cuff C, after the latter has been attached to the wrist band B, of the sleeve S, as will be 100 understood more particularly by reference to Fig. 2, of the drawings, by which it will be seen that said cuff button holes c, c, are fully exposed beyond the ends of the flap A, whereas the band stud buttons b^x, and 105 b^x, coincide with the coincidental cuff holes c^x, c^x, with which they engage, are covered by the flap A, when the said flap is folded over the wrist band B.

The cuff C, is foldable on the line f, f, 110 Figs. 2, 4, and 5, the outer fold c', being of greater width than the inner fold c², and

of sufficient width to cover both said inner fold c^2 , and the concealing flap A, when folded thereover, as in Fig. 1.

The coincidental button holes c^x , c^y , on 5 the inner fold c^3 , of the cuff C, provided for engagement with the stud buttons b^x , b^y , of the wrist band B, may be either of the socket type indicated in Fig. 4, or may be 10 of the slit form of button hole indicated in Fig. 5, as may be preferred, the action and result being the same in either case in that suitable provision is made for detachably securing the cuff C, to the sleeve S. Where metallic button holes c^x , are used as 15 in Fig. 4, they either extend through the cuff, like eyelets, or are duplicated on each face thereof. And in this connection it may be stated that while I herein show the stud buttons b^x , as positioned on the sleeve wrist 20 band B, and the coinciding button holes c^x , c^y , on the cuff, it is obvious that the alternative arrangement may be resorted to if preferred, with like results,—i. e., the stud buttons b^x , may be affixed to the cuff C, and 25 coinciding button holes c^x , may be formed on the wrist band B, so that I do not limit myself in this respect, the essential feature being the provision of interlocking means whereby the cuff may be attached to the 30 wrist band substantially as set forth.

The lateral edges c^3 , of the inner fold c^2 , of the cuff C, are preferably curved or inclined inward as shown in Figs. 2, 4 and 5, so as to be well within the circumferential 35 edge of the outer fold c' , when the latter is positioned as in Fig 1, thereby attaining a neat and symmetrical external appearance

The advantages of my detachable, reversible, and interchangeable cuff will be readily understood; and the function of the concealing flap A, in affording the appearance, externally, of an integral structure of cuff and sleeve, is an additional benefit attained by my invention which will be fully appreciated by the user. 40

What I claim as my invention and desire to secure by Letters Patent is,

1. In combination, a sleeve the wrist band of which is formed with a plurality of fastening means, a detachable foldable and reversible cuff, a plurality of coincidental fastening means thereon adapted to engage from either side of the cuff with the said fastening means on the sleeve wrist band, and a flap attached to the sleeve and adapted 50 to fold over and conceal said sleeve and cuff securing means, for the purpose described. 55

2. In combination, a sleeve the wrist band of which is formed with a plurality of fastening means, a detachable foldable and reversible cuff, a plurality of coincidental fastening means thereon adapted to engage from either side of the cuff with the said fastening means on the sleeve wrist band, and a flap attached to the sleeve and adapted to fold over and conceal said sleeve and cuff securing means, said concealing flap being formed with sloping centrally convergent end edges for the purpose described. 60 65
